METHOD OF ANCHORING THE ELASTIC
THREADS OF FABRIC AND THE PRODUCT
PRODUCED BY THE METHOD

Norman W. Cook, Englewood, N. J.

Application May 13, 1941, Serial No. 393,294

12 Claims. (Cl. 28—77)

My invention relates to a method of attaching or anchoring the elastic threads of woven, knitted, netted or braided elastic fabrics, to prevent the displacement or drawing back of the elastic threads, and to the product produced by the method.

As is well known, elastic fabric, woven, knitted, netted or braided, embodies elastic threads which are frequently placed under tension when the fabric is being formed. With elastic fabric, particularly where the elastic threads are under tension when the fabric is being formed, there is a tendency for the elastic threads to become displaced or to pull back. This pulling back of the elastic threads frequently occurs when the elastic fabric is cut into a suitable size or shape and sewed in place. The tendency for the elastic threads to pull back is also increased during the use of a garment or article embodying elastic fabric. It therefore results that garments made in part or in whole of elastic fabrics have the undesirable property of losing their elasticity and fine appearance at or near the seams where different sections are sewn together. These garments embrace such wearing apparel as corsets, girdles, brassières, slips, underwear, ladies' panties, shorts, gloves, bathing suits, athletic supporters, pajamas, surgical garments and other articles to be applied to the body and which are formed in whole or in part of elastic fabric.

Attempts have heretofore been made to solve this problem but they have not proven satisfactory. It has been proposed to coat the edge of elastic fabric with a rubber cement which coated edge is subsequently subjected to heat for vulcanizing such edge, as shown in Patent 1,672,432. It has been proposed to apply a liquid cement to the surface of the elastic fabric and then apply a strip of unvulcanized rubber to the coated surface subsequently to which heat and pressure is applied to the rubber strip. This method is shown in Patent 1,882,642. In Patent 2,136,742 the edges of the elastic fabric are coated with a rubber solution such as latex which is allowed to dry therefrom by anchoring the rubber threads against displacement.

These former methods are objectionable for several reasons. They all involve the application of a liquid cement or liquid chemical to the elastic fabric, which is a slow and expensive step. The methods disclosed in the patents also produce a seam or surface which is bulky and sticky, having a texture or appearance quite different from that of the elastic fabric, and is therefore unsightly.

In accordance with my method the elastic fabric has applied thereto a material which is normally in the form of a solid, is flexible, dry and non-tacky, but which alone is a potential adhesive, and will be activated into adhesiveness by heat, without the use of a liquid cement or solvent and which will instantly set when the heat is removed therefrom. The potential adhesive is preferably carried by a fabric strip, although I contemplate using the potential adhesive without the fabric strip.

In one embodiment of the invention the potential adhesive is secured to one face of a preferably thin linear woven fabric and the thin fabric is then arranged upon the elastic fabric, with the potential adhesive next to the elastic fabric. The assembled parts are then subjected to the action of heat and pressure.

I also contemplate omitting the preferably thin fabric strip and applying a strip of the potential adhesive to the surface of the elastic fabric, to be followed by the heat treatment and pressure.

I further contemplate forming the potentially adhesive material in the form of a thread and sewing this thread into the elastic fabric. This will bring the thread potential adhesive well into and through the fabric in close relation to the elastic threads and this will be followed by the heat treatment in the presence of pressure.

In the accompanying drawings forming a part of this application and in which like numerals are employed to designate like parts throughout the same,

Figure 1 is a perspective view of the meeting ends of an elastic band or fabric, showing partly applied thereto a strip or binder carrying the thermoplastic adhesive material.

Figure 2 is a longitudinal section taken on line 2—2 of Figure 1.

Figure 3 is a similar view, showing the application of heat and pressure to the associated elements.

Figure 4 is a transverse section taken on line 4—4 of Figure 3.

Figure 5 is a perspective view of the completed seam or article.

Figure 6 is a perspective view of one end of an elastic band or strip showing a binder folded about the edge of the same in accordance with a modified form of the invention.

Figure 7 is a longitudinal section taken on line 7—7 of Figure 6.

Figure 8 is a similar view, showing the band subjected to pressure and heat,

Figure 9 is a perspective view of the end of the band, after the heating and pressing step.

Figure 10 is a longitudinal section through the band, after the heating and pressing step and showing the manner of stitching garment parts to the band.

Figure 11 is a similar view showing the garment parts folded over the line of stitching.

Figure 12 is a perspective view of an elastic band showing the thermoplastic adhesive material sewed into the same.

Figure 14 is a detailed section taken on line 14—14 of Figure 13.

Figure 15 is a view similar to Figure 13, showing the heating irons applied to the fabric having the stitching of thermoplastic adhesive material.

Figure 16 is a similar view after the heating operation, showing the finished product.

Figure 17 is a view similar to Figure 14, after the heating step and showing the finished product, and,

Figure 18 is a perspective view of the end of the elastic band, showing the finished product.

In Figures 1 to 5, inclusive, the numeral 10 designates a section or sections of an elastic fabric, which may be woven, knitted, netted, or braided, and having elastic or rubber threads 11, combined with the usual non-elastic fibrous threads or yarn. The elastic fabric may be of a one-way or two-way stretch. The meeting edges of the sections 10 are shown as covered by the strips of fabric 12, arranged above and below the same, and the inner surfaces of the fabric strips 12 are coated with the potential adhesive 13, arranged next to the elastic fabric 10. The adhesive 13 applied to the surface of the fabric strip 12 is dissolved in a suitable solvent or dispersed in an aqueous solution and spread upon the surface of the fabric 12 throughout its length. The solvent is driven off and the potential adhesive 13 remains deposited upon the surface of the fabric 12. This fabric is preferably thin, to prevent the formation of a thick or bulky seam, and the thin fabric 12 is closely woven so that the potential adhesive 13 will not pass to the opposite or outer face of the fabric 12. The fabric or binder 12 will possess the same general appearance as the associated elastic fabric 10, and may be made in the same color, if desired. The fabric 12 completely covers or conceals the potential adhesive 13. The coating or film of the potential adhesive 13 is normally in a solid form, is flexible, dry, and non-tacky, and which alone is a thermoplastic potential adhesive. As illustrations of compositions which I employ in normally solid forms and which alone are thermoplastic potential adhesives, I may use (1) uncured rubber which is compounded with curing ingredients and anti-oxidants, (2) uncured rubber treated with an anti-oxidant, (3) methyl or ethyl polyacrylate, (4) polymerized isopolybutene, (5) polymerized vinyl chloride or vinyl acetate or copolymers of both, (6) plasticized casein, (7) polymerized vinylidene chloride. Of these substances the plasticized casein and vulcanizable rubber are only initially thermoplastic, while the other potential adhesives are permanently thermoplastic. All of the potential adhesives will substantially instantly set or harden upon the removal of the heat.

The next step in the method is to subject the potentially adhesive material 13 to the action of heat to render the same plastic and adhesive, in the presence of pressure. This may be effected by arranging the elements to be secured together between heating and pressing jaws, which are brought together to subject the sections of elastic fabric 10, strips 12 and the potential adhesive 13 to the desired heat and pressure. I have found that satisfactory results can be obtained by heating the potentially adhesive material 13 to a temperature of from 200° F. to 218° F., although these temperatures may be varied. The temperatures at which the different potentially adhesive materials mentioned will become plastic and adhesive is known in the trade, and the temperature may be regulated as may be found advantageous. As an illustration, the polymerized vinylidene chloride may be rendered adhesive by heating the same to substantially 250° F. The heating and pressing jaws 14 may be heated by any suitable means. I preferably subject the sections of fabric 10 and associated elements to a pressure of from twenty-five pounds to fifty pounds to the square inch applied thereto by the jaws 14. The pressure is continued during the heating period and during this period the material 13 is rendered plastic and adhesive and is forced into the interstices or spaces of the fabric sections 10 and will contact with the elastic or rubber strands 11 to anchor or bind the same within the fabric. The heat treatment need only be for a short time, practically momentarily. As soon as the irons 14 are removed from the strip 12 the thermoplastic material 13 sets substantially instantly thereby securely bonding or anchoring the elastic or rubber threads 12 to the fabric, thus positively holding them against displacement or pulling out action. During the heating and pressure treatment the plastic material 13 will not extend through the closely woven fabric 12 to its outer surface. The outer surface of the fabric 12 therefore remains clean, and will correspond generally in appearance to the elastic fabric 10, and may be of the same color, thus affording a seam of attractive appearance. A further advantage in the method is that the pressing action compresses the seam including the strips 12 and portions of the elastic fabric 10, so that the seam has substantially the same thickness as the sections 10, when freed from compression. As the thermoplastic material 13 sets substantially instantly, it also holds the seam against transverse expansion, whereby the seam has its surface substantially flush with the surfaces of the fabric sections 10. This produces a neat and attractive seam having a slender appearance.

The meeting edges of the elastic fabric sections 10 are further secured together by a zig-zag line of stitching 15, passing through the fabric strips 12 and sections 10. This zig-zag line of stitching is preferably made after the heating and pressing operation, although the invention is not restricted to this order of the steps, as the strips 12 could be stitched to the sections 10 prior to the heating and pressing steps.

In Figures 6 to 11 inclusive, I have shown a modification of the invention. In these figures, the numeral 16 designates a section of elastic fabric embodying elastic or rubber threads 17 and non-elastic fibrous threads or yarn. The fabric 16 may be woven, netted, knitted, or braided. The numeral 18 designates a fabric strip or binder which is U-shaped in cross-section and is placed about the edge of the fabric 16. This strip or

binder has its inner face coated with a thermoplastic potential adhesive 19, and the adhesive 19 is the same as the coating 13 of the strip 12 in Figure 1. This adhesive 19 may be any of the potential adhesives mentioned in connection with the adhesive 13 described with the first form of the invention. The same steps of heating and pressing are followed as described in connection with the first form of the invention, excepting the precise stitching step. The parts 16 and 18 are subjected to heat and pressure and the thermoplastic adhesive 19 is rendered plastic and adhesive and enters the interstices or spaces of the elastic fabric 16 to contact with the elastic threads thereof and anchors or binds the elastic threads to the non-elastic fibrous yarn. This thermoplastic material sets instantly upon the release of pressure and heat and the edge produced by the binding 18 will have substantially the same thickness as the normal thickness of the section of fabric 16. The fabric or binding is thin and formed of a closely woven fabric, corresponding to the strip 12, and the plasticized adhesive will not pass to the outer surface of the binder 18, for the same reasons as stated in connection with the strip 12.

When it is desired to secure the elastic fabric 16 to a garment or the like this may be effected by placing parts 20 of the garment upon opposite sides of the binder 18 and stitching the elements 20, 18, and 16 together by a line of stitching 21, subsequent to which the fabric parts 20 are folded over the line of stitching. This should be regarded as one illustration of the manner of attaching the elastic section to a garment part.

In Figures 12 to 18, inclusive, I have shown a still further modification of the invention. In these figures, the numeral 21 designates an elastic fabric, woven, knitted, netted, or braided, having elastic or rubber threads 22 and non-elastic fibrous threads or yarn. Adjacent to the cut edge of the elastic fabric, I sew through the same a line of stitching 23. This line of stitching is made from a thread formed of a thermoplastic potential adhesive. Any of the thermoplastic potential adhesives recited in connection with the first form of the invention may be used. Satisfactory results are had by using polymerized vinylidene chloride. The thread may be formed entirely of polymerized vinylidene chloride or the thread may have a core 24 formed of cotton or the like having a coating 25 of polymerized vinylidene chloride. When the thread is sewn through the fabric 21 it contacts with or is disposed in close relation to the elastic or rubber threads 22. After the sewing operation, the edge of the fabric 21 adjacent to the stitching 23 is subjected to the heating step by means of the heating irons 14 so that the thermoplastic material is rendered adhesive and adheres to the elastic threads 22 within the fabric. The same action will occur if the threads 23 are formed entirely from the thermoplastic material or are coated with the thermoplastic material. By the sewing of the thermoplastic material into and through the fabric 21, very little, if any, pressure is necessary to be applied to the fabric, whereby the edge of the fabric is not materially compressed.

In all forms of the invention I employ a normally solid material which alone is a thermoplastic potential adhesive. This material may be rendered quickly or instantly plastic by the action of heat and will as quickly set, upon the removal of the heat. The material may be vul-

canizable or non-vulcanizable, as illustrated by the several examples furnished. The use of all of my materials eliminate the step of applying a liquid chemical to the fabric.

The present invention may be embodied in various articles, such as the garter shown in Figure 1 of the Herbener Patent 2,136,742, the bands with the stiffening ribs and the girdle shown in the various views of the Herbener patent, or the insert 12 of the Spalding Patent 1,672,432, or in other articles which are to be worn and wherein section or sections of elastic fabric are connected to other parts.

It is to be understood that the forms of my invention herewith shown and described are to be taken as preferred examples of the same and that various changes in the shape, size, and arrangement of parts may be resorted to, and that changes in the order of the steps of the method, and that known chemical equivalents may be used, without departing from the spirit of my invention or the scope of the subjoined claims.

Having thus described my invention, what I claim is:

1. The method of treating elastic fabric having elastic threads, comprising inserting into the previously formed fabric a normally solid thermoplastic potentially adhesive material while in the solid condition, and then subjecting the thermoplastic material to the action of heat to plasticize the same so that it anchors the elastic threads within the fabric.

2. The method of treating elastic fabric having elastic threads, comprising sewing into the fabric a strand embodying normally solid thermoplastic potentially adhesive material, and then subjecting the thermoplastic material to the action of heat to plasticize the same so that it anchors the elastic threads within the fabric.

3. The method of treating elastic fabric having elastic threads, comprising sewing into the fabric transversely of the elastic threads a strand embodying normally solid thermoplastic potentially adhesive material, and then subjecting the thermoplastic material to the action of heat to plasticize the same so that it anchors the elastic threads within the fabric.

4. The method of treating elastic fabric having elastic threads, comprising sewing into the fabric transversely of the elastic threads a strand formed entirely of a solid thermoplastic potentially adhesive material, and then subjecting the thermoplastic material to the action of heat to plasticize the same so that it anchors the elastic threads within the fabric.

5. The method of treating elastic fabric having elastic threads, comprising sewing into the fabric transversely of the elastic threads a strand having a fibrous core and a coating of a solid thermoplastic potentially adhesive material, and then subjecting the thermoplastic material to the action of heat to plasticize the same so that it anchors the elastic threads within the fabric.

6. The method of treating elastic fabric having spaced elastic threads, comprising passing into the previously formed fabric through its face a normally solid thermoplastic potentially adhesive material while in a solid condition at a plurality of spaced points and thereby locating such solid material adjacent to the elastic threads, and then subjecting the solid thermoplastic material to the action of heat to plasticize the same so that it engages and anchors the elastic threads within the fabric.

7. The method of treating elastic fabric having an elastic thread, comprising passing into the previously formed fabric at generally a right angle to the plane of the fabric a section of a normally solid thermoplastic material while in the solid condition and at a point adjacent to the elastic thread, and then subjecting the thermoplastic material to the action of heat to plasticize the same so that it anchors the elastic threads within the fabric.

8. The method of treating elastic fabric having longitudinally extending elastic threads, comprising inserting into the previously formed fabric at generally a right angle to the surface of the fabric and at points spaced transversely of the fabric a normally solid thermoplastic potentially adhesive material while in the solid condition and thereby locating such material adjacent to the longitudinal elastic threads, and then subjecting the thermoplastic material to the action of heat to plasticize the same so that it anchors the elastic threads within the fabric.

9. As an article of manufacture, a completed elastic fabric having elastic threads and a cut or raw edge, and means to anchor the elastic threads within the fabric, said anchoring means being disposed only adjacent to the cut or raw edge and including a normally solid thermoplastic potentially adhesive material sewed into the fabric adjacent to the elastic threads while the material is solid and subsequently heated to

render the same plastic and then allowed to harden.

10. As an article of manufacture, an elastic fabric having elastic threads and a cut or raw edge and a normally solid thermoplastic potentially adhesive material sewed into the fabric adjacent to the cut or raw edge and while in a solid condition and subsequently heated to render the same plastic and to cause the same to anchor the elastic threads in the fabric.

11. As an article of manufacture, a completed elastic fabric having spaced rubber threads and having a cut or raw edge, and a solid thermoplastic potentially adhesive material forced into the fabric while in the solid condition and adjacent to the elastic threads the cut or raw edge and subsequently heated to render the same plastic so that it anchors the elastic threads within the fabric.

12. The method of treating an elastic fabric having spaced rubber threads and a cut or raw edge, comprising passing into the previously formed fabric through its face and only adjacent to its cut or raw edge a normally solid thermoplastic potentially adhesive material while in a solid condition at a plurality of spaced points and locating such solid material adjacent to the rubber threads, and then subjecting the solid thermoplastic material to the action of heat to plasticize the same so that it engages and anchors the rubber threads within the fabric.

NORMAN W. COOK.
